**AUTOMATIC ADJUSTMENT AND COMPENSATION
OF THE SECONDARY VOLTAGE OF A TRANS-
FORMER**

6 Claims. (Cl. 323—43.5)

This invention relates to an improved method for automatic adjustment and compensation of the secondary voltage of a transformer, the method being based on the change of the number of turns of the primary winding.

There exists a great number of apparatuses in which the working voltage has to be changed within a certain range. For example in the case of large X-ray instruments the values of actually used high voltages vary from 40 to 150 kilovolts (peak values). Changes in working voltage are also necessary, in the case of electric filters, electrostatic sorting equipments, supply sources and in many other instances.

There are three generally known methods for changing the value of the secondary voltage. In the first method, an auto transformer is connected across the primary winding. In the second arrangement, the number of turns of the secondary winding is varied. In the third arrangement, the number of turns of the primary winding is varied.

These known arrangements have various disadvantages. In the case of the first arrangement mentioned above, a separate high power auto-transformer must be built into the apparatus, and this involves additional expense. Variations of the number of turns of the secondary winding, while eliminating the necessity for the use of the extra autotransformer, involves direct variation of the relatively very high secondary voltage. In turn, this introduces substantial problems with respect to insulation and to possible arcing and the like. The third arrangement, which is that of varying the number of turns of the primary winding, does not have the disadvantages of the first two arrangements mentioned above.

Nevertheless, this third arrangement has not been used up to the present for various reasons. One reason is that it has not been known how to control and stabilize the secondary voltage in such a way that the device could operate fully automatically and with a great degree of accuracy within the whole working range. An other difficulty of this third arrangement resides in the fact that the potentiometer in the automatic controller must have a hyperbolic characteristic and that the sensitivity of the control relay for the servo-system must be a quadratic function of the difference between the maximum and minimum value of the voltage to be regulated.

These difficulties with respect to the third-mentioned control arrangement have prevented such arrangement from being utilized in practical operation.

The method of voltage control, or the secondary voltage control system, to which this invention relates eliminates the afore-mentioned drawbacks in that it suggests an accurately working practicable device based on the third principle mentioned above. A substantial advantage of the invention system consists in that the sensing element need not be calibrated as to its sensitivity since the sensitivity of the sensing element can be constant, thus enabling the system to incorporate electronic components and circuitry. For an understanding of the principles of the present invention, reference is made to the following description of a typical embodiment thereof as illus-

2

trated in the accompanying drawings. In the drawings:

FIGS. 1a, 1b and 1c are schematic wiring diagrams illustrating the three known secondary voltage control systems mentioned above;

5 FIG. 2 is a somewhat more detailed schematic wiring diagram of a control system based upon the principle of controlling the secondary voltage by varying the number of turns of the primary winding;

10 FIG. 3 is a somewhat more detailed schematic wiring diagram illustrating a secondary voltage control system embodying the invention; and

FIG. 4 is a graph illustrating the principles involved in the invention control system.

15 FIG. 1a illustrates a system for controlling the secondary voltage of a transformer Tra by the use of an auto transformer AT which is connected across the primary winding of the transformer. KV represents a meter, and the load, such as an X-ray tube, as indicated as L .

20 FIG. 1b illustrates an arrangement for controlling the secondary voltage of the transformer Tra by varying the number of turns of the secondary winding, this being effected by the use of a moveable contact MC , as schematically illustrated in FIG. 1b.

25 FIG. 1c schematically illustrates a secondary voltage control system which is based upon the principle of varying the number of turns of the primary winding. In this arrangement, upon which the present invention is an improvement, the number of turns of the primary winding is varied by means of an adjustable contact MC' .

30 The basic transformer equation suggests that for a constant number of secondary turns the number of primary turns can be computed for each chosen value of both the main voltage and the secondary voltage.

35 The basic transformer equation is diagrammatically illustrated in the graph of FIG. 4 covering the usual working ranges. At the same time, this graph also shows the nomograph of the equation expressing the regulating action of the device according to this invention.

40 Prior to go more deeply into the description of circuits shown in FIGS. 2 and 3 yet us explain the meaning of abbreviations and symbols to be found in these figures:

P_1 —potentiometer for adjusting kilovolts

J_1 —moving contact coupled to the kv -index

45 P_2 —control potentiometer

J_2 —moving contact of P_2 coupled to the device changing the number of primary turns

PR—polarized relay or other differential control device

n —relay for "up" direction

50 d —relay for "down" direction

M —electro-motor

TR—main transformer

J_3 —main transformer moving contact, mechanically linked with J_2

55 J_4 —moving contact for changing the pick-up sensitivity (only in FIG. 2)

P_4 —potentiometer for changing the pick-up sensitivity (only in FIG. 2)

A —hyperbolic characteristic

60 V_1 —unstabilized volts

V_2 —stabilized volts.

65 Referring to FIG. 2, the potentiometer moving contact J_1 is associated with the scale of the control device. The corresponding potentiometer P_1 is linear and a stabilized D.C. voltage is applied to its terminals. The control moving contacts J_3 , which adjusts the number of primary turns, is coupled to the moving contact J_2 of the hyperbolic potentiometer P_2 . This potentiometer is connected across a D.C. voltage which is proportional to the voltage of that phase of the mains x, y, z , which is applied across the main transformer TR. Both moving contacts J_1 and J_2

characteristic. It will be noted, from reference to the hyperbolic characteristic indicated at A, and from reference to the scale, that the voltage adjustment increases in a downward direction, across the potentiometer P_1 , as compared to the potentiometer P_1 of FIG. 2 wherein the voltage increases in an upward direction. Thus, the arrangement of FIG. 3 corresponds to the aforementioned mathematical analysis, wherein it was pointed out that the control voltage E_x is inversely proportional to the secondary voltage of the transformer TR, and wherein it was pointed out that the equation determining the high voltage adjustment for a constant voltage of the mains is an equation for a hyperbola.

While a specific embodiment of the invention has been shown and described in detail to illustrate the application of the principles of the invention, it will be understood that the invention may be embodied otherwise without departing from such principles.

What I claim is:

1. In a control system for automatically controlling the secondary voltage of a transformer by correctively adjusting the number of primary winding turns of the transformer responsive to deviation of the secondary voltage from a preset value as a result of variation in the supply voltage impressed across the transformer primary winding, the improvement comprising a first contact adjustable along said primary winding to vary the number of turns thereof effectively in circuit; a first linear potentiometer including a second contact adjustable therealong and mechanically coupled to said first contact; means for applying a stabilized D.C. voltage across said first potentiometer; scale means; second potentiometer means; a third contact adjustable along said second potentiometer means with reference to said scale means to preset said voltage

value; a servo-system for conjointly adjusting said first and second contacts; means for impressing, across said second potentiometer means, a D.C. voltage proportional to the A.C. voltage impressed across the primary winding of said transformer, to provide a control voltage; and differential responsive control means for correctively operating said servo-system responsive to a difference in the adjusted D.C. voltages represented by said second contact and said third contact; at least one of said second potentiometer means and said scale means being hyperbolic.

5 2. In a control system improvement, as claimed in claim 1, said control voltage impressed across said second potentiometer means being inversely proportional to the secondary voltage of said transformer.

10 3. In the control system improvement, as claimed in claim 1, the sensitivity of said differential responsive control element being constant over the complete regulating range of the system.

4. In a control system improvement, as claimed in claim 1, said second potentiometer means comprising a linear potentiometer and said scale means comprising a hyperbolic scale.

20 5. In a control system improvement, as claimed in claim 1, said second potentiometer means comprising a hyperbolic potentiometer and said scale means comprising a linear scale.

25 6. In a control system improvement, as claimed in claim 1, the combination of said second potentiometer means and said scale means having a hyperbolic characteristic.
